RECLOSING CIRCUIT BREAKER

Theodore Birkenmaier, St. Louis, and Carl E. Mosley, Overland, Mo., assignors to W. N. Matthews Corporation, St. Louis, Mo., a corporation of Missouri

Application June 8, 1942, Serial No. 446,216

28 Claims. (Cl. 200—89)

This invention relates to reclosing circuit breakers or switches, and with regard to certain more specific features to repeater switches of this class.

Among the several objects of the invention may be noted the provision of a solenoid-operated repeater switch in which is avoided the application to the switch linkage of the often violent action of the solenoid, such as is caused by heavy fault current; the provision of apparatus of the class described which operates reliably and consistently regardless of the expected variations in force of operation provided by a solenoid control; the provision of apparatus of the class described which more closely approaches desirable inverse time-current characteristics than can be expected from the ordinary solenoid-operated switches; the provision of a device of this class which is trip-free, that is, one which cannot be manually closed and remain shut on a dead short or overload; and the provision of apparatus of the class described which will not be operated unnecessarily under conditions of harmless transients. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which is illustrated one of various possible embodiments of the invention,

Fig. 1 is a front elevation, parts being broken away for clarity, the parts being in circuit-closing position;

Fig. 2 is a right-side elevation of Fig. 1, parts being broken away;

Fig. 3 is a top plan view of Fig. 1, parts being broken away;

Fig. 4 is an enlarged fragmentary sectional detail of a timing mechanism, being taken on line 4—4 of Fig. 2;

Fig. 5 is a fragmentary horizontal section taken on line 5—5 of Fig. 4;

Fig. 6 is a fragmentary horizontal section taken on line 6—6 of Fig. 4;

Fig. 7 is a fragmentary horizontal section taken on line 7—7 of Fig. 4;

Fig. 8 is a fragmentary side elevation similar to Fig. 1, but showing certain parts in a preliminary solenoid-released condition;

Fig. 9 is a view similar to Fig. 1, showing a

progressive condition of parts in which additional releasing functions have occurred beyond those shown in Fig. 8;

Figs. 10 and 11 are fragmentary views of parts 5 of Fig. 9 showing successively advanced positions of certain parts;

Figs. 12 and 13 are views similar to Fig. 1 showing additional positions of parts; and,

Fig. 14 is a view showing a trip-free condition. 10 Similar reference characters indicate corresponding parts throughout the several views of the drawings.

Although the present invention is shown as applied to an air circuit breaker, it is to be understood that the principles thereof may be applied to oil and similar circuit breakers in other ambient mediums.

Heretofore, overload-current-responsive solenoids have been used for initiating the action of 20 circuit breakers, but their characteristics have been found to be quite variable, since the operating force on the armature of the solenoid is variable, being about proportional to the ampere turns of current. Consequently under heavy current operation they tend to operate the circuit breaker mechanism more violently; in fact so violently in many instances that damage is done to the mechanical linkage. In addition, switches which are solenoid operated per se do not have 30 desirable inverse time-current characteristics.

Referring now more particularly to Figs. 1-3 wherein the new circuit breaker is shown in circuit closing position, numeral 1 indicates a base by means of which the apparatus is mounted, preferably in an elevated position. Spaced from this base 1 on four pillars 3 is an insulating platform or head 5 which is counterbored to receive four movable terminals or circuit contacts 7, two being on each side of the apparatus. Each contact or terminal 7 is resiliently biased downward by a spring 9, being limited in downward movement by seating on the end of an insulating tube 11 screwed into the head 5 from below. The four tubes 11 are preferably made of horn fiber or like 40 de-ionizing substance for de-ionizing any arcs that may form therein.

Line wires are indicated at 13 and 15. These carry the load and each is connected to one of the terminals 7. One of the other two terminals 7 is in conductive relationship with a solenoid 17 by way of lead wires 19 and 21. The wire 21 is connected to a conducting standard 23 which forms a fulcrum for a conducting lever 25. One end of this lever 25 is in conductive relationship 50 with a conducting bimetallic helical thermostatic

member 27. The thermostatic member or element 27 comprises bimetal having elements of different coefficients of thermal expansion rigidly connected along their lengths and wound progressively about a first axis which in turn is extended progressively about a second axis. The lower end is conductively attached to a conducting block 29. This block 29 is in conductive relationship through wire 31 with another one of the terminals 7. Thus if the terminals on opposite sides of the apparatus be connected by a suitable switch, a circuit is closed in series through the solenoid 17 and through the thermostatic element 27 (Fig. 3).

Details of the thermostatic element may be found in Parsons United States Patent 2,121,259, dated June 21, 1938, wherein it is made clear that such a thermostat will contract along the axis of the major helix when heated, provided that the metal component having the lesser coefficient of thermal expansion is wound outside on the small helix, and the metal component having the greater coefficient of expansion is wound on the inside of said small helix. Thus any heating of the element 27 by excessive current therein for a long enough time results in a substantial shortening of the length of the element 27, thus drawing down the end of the arm 25. The time required for shortening is in an inverse ratio to current. The results of this action, along with that of the solenoid 17, will be traced hereinafter. It is to be understood that the bimetallic characteristics of the thermostat are exemplary of other composite metallic combinations.

The switch means for closing the circuit across the pairs of terminals 7 consists of a pair of conducting bars 30 which are mounted crosswise upon an insulating crosshead 33, the latter being supported upon the upper end of a slider 35. The slider 35 and the bars 30 are not in conductive relationship. Each bar 30 carries at each opposite end a conducting switch plug 37 which is rigidly attached as indicated by the nuts 39. The plugs 37 are long enough so that when the bars 30 are up, contacts are made with the resilient terminals 7. Thus, when the slider 35 is up, the circuit is closed at four points. This connects the solenoid 17 and the thermostat 27 in series with one another and with the switch constituted by the bars 30, plugs 37 and terminals 7. The circuit when opened breaks at four points, each within one of the arc-suppressing fiber tubes 11.

The slide 35 is constrained to move vertically in guides 41 and at its lower end carries a lateral extension 43 to which is attached a tension spring 45 supported by bracket 47. The spring 45 places a continuous upward bias upon the slide 35 and therefore normally biases the terminal-engaging plugs 37 into line closing position against the resilient terminals 7 (see Figs. 1 and 8).

The guides 41 are associated with a subframe 49 supported upon a rigid supporting bracket 51. This subframe carries various items to be described, including a pivot 53 for a bell-crank 55 to the right of the slider 35 (Fig. 1). The downwardly extending arm of this bell-crank 55 is formed as a hook 57 engaging a notch 59 in the slider 35. This forms a latch. The lateral arm of the bell-crank 55 is pivoted at 61 to vertical control link 63 made of insulating material. The link 63 passes through a suitable opening in the member 5 and extends upward into pivoted relation with the rocker arm 25, as indicated at 65 (Fig. 2).

The purpose of the latch 57, 59 is to hold the slider 35 up against downward bias which may be applied thereto through a drive link 67. This link 67 is pinned to the slider 35 at 69 and is pinned to a crank 71 at 70. If the crank 71 is rotated counterclockwise, it will drive down the link 67, and this, through pivot 69, tends to drive down the slider 35. However, downward motion is normally blocked by the latch 57, 59. Latch 57, 59 does not block upward movement.

The crank 71 is keyed upon a shaft 73 which is rotary in the subframe 49. An inner bearing plate for this shaft is shown at 75 (Fig. 4). Keyed to shaft 73 is also a rotary cam latch 77 which has a generally spiral shape, thus forming a catch portion 79.

Cooperating with the catch 79 is a sliding holding plate 81 (Figs. 4 and 5). This is slideable in a stationary guide 83 which is attached to the frame 49. An opening 85 in plate 81 accommodates the lower end 87 of a lever 89 pivoted at 91 to the frame 49. This lever 89 reaches up through an opening in the plate 5 and is pivoted at 91 to a connecting link 93, part of which is insulated as shown at 95. This link 93 is pivoted at 97 to the magnetic armature 99 of the solenoid 17. The armature slides through an opening in the solenoid and is normally biased toward the left in Fig. 1 by a spring 101. The link 93 slides upon a support 103. Thus, energization of the solenoid 17 results in pulling the top of lever 89 to the right and moving its lower end 87 to the left. This moves the slide 81 to the left from under the cam latch 79. When the solenoid 17 is deenergized, its spring 101 drives the slide 81 back against the cam latch 77, which being spirally shaped allows the plate 81 to move in behind catch 79 on a subsequent revolution of 77.

The catch 79 is ordinarily biased against the slide or latch 81, being driven that way by a gear train 104, 105, 107 borne in the frame 49. The gear 107 is rigidly organized with a ratchet 109. Next to the ratchet is a rotary pawl crank 111 to which is pivoted at 113 a pawl 115. The latter is normally biased by a spring 117 into engagement with the teeth of the ratchet 109. The pawl crank 111 is on a shaft 119 which is driven or biased by means of a main power spring 121 reacting at 123 against an extension 125 of said frame 49. The spring may be wound up by rotating a drum 127 from a pull chain 129. This tensions the spring and retracts or sets back the pawl 115 clockwise with respect to the ratchet 109. Since the spring 121 biases the pawl 115 counterclockwise (Fig. 4), it drives or tends to drive the gears 107, 105, 104 as indicated by the arrows, thus biasing the crank 71 counterclockwise. This also drives the catch 79 against the slide 81, unless the slide 81 is pulled out from under the catch by action of the solenoid 17, in which event the spring drives the crank 71 through the ratchet and the gear train.

However, even when the slide 81 is pulled out from under the catch 79 it is not possible for the spring 121 to move the gear train and crank for more than a very short distance, as determined by the slack in the mechanism 71, 67, 35. This is because this mechanism tends to drive down the slider 35, but the slider is held by the latch 57, 59 so long as the bell-crank 55 is not moved counterclockwise (see Fig. 8).

When the latch 57, 59 is opened (as by shrinkage of the thermostatic coil 27 under flow of excess current therethrough which causes heating), then the power spring 121 (after release of

the catch 79 by action of the solenoid 17 may drive the linkage 71, 67, 35. This withdraws the terminal-engaging elements 37 from the terminals 7, thus effecting a four-point opening of the circuit. The driving action of the spring 121 is enough to overcome the tension of spring 45. Also, the driving action not only draws down the slider 35, but ultimately biases it up again during a complete cycle of movement. This provides the reclosing action.

In order to provide time delay for the reclosing action, the slider 35, during upward movement, temporarily is linked up with an escapement mechanism which will now be described.

The escapement mechanism consists of a ratchet sector 131 which has a motion limiting tail piece 133. The tail piece 133 limits counterclockwise motion of the sector 131 by contact with a stop 135 (see Fig. 11). Clockwise motion is also limited by contact of the sector 131 with this same stop on its other side (see Fig 1). The sector 131 consists of three teeth A, B and C adapted temporarily to be engaged by a catch 137 on an arm 139 which is pivoted at 141 to the slider 35.

A spring 143 biases the arm 139 clockwise normally to effect engagement between the rising catch 137 and one of the teeth A, B or C. When the slider 35 moves down, the catch 137 rides over any tooth A, B or C which is in its path, due to the resilience of the spring 143 permitting angling of the member 139. The normal position of sector 131 is with tooth A in position to be engaged by the rising catch 137.

For time-delay action, the sector 131 is keyed to a shaft 145 which is attached to a spring 147 reacting on the frame 49 at 149. The spring 147 is arranged normally to bias the sector 131 clockwise to the position shown in Fig. 1.

In order that both clockwise and counterclockwise action of the sector 131 shall be delayed action, the shaft 145 is provided with an attached gear 151 which meshes with a pinion 153. Carried on the same shaft 155 with the pinion 153 attached is also a two-way escapement wheel 157. The teeth on this wheel alternately engage the swinging pallets 159 of an oscillating anchor 161 pivoted at 163. The opposite ends of this anchor 161 carry adjustable inertia weights 165. These weights may be adjusted in position on the anchor by set screws 167, thus enabling the escapement to be timed for different periods of delay. By changing the position of the teeth on the sector 131 and co-ordinating the teeth with the gear train 104, 105 and 107, it is also possible and desirable to provide different time delay intervals between reclosing operations.

Thus if, after having been driven down, the catch 137 engages one of the teeth A, B or C during its upward travel, the upward motion of the slider 35 is delayed by the resistance to motion of the sector 131 which is introduced by the escapement mechanism. This mechanism, for identification, consists of the gears 151, 153, along with the shaft 155, ratchet 157 and anchor 161. Thus the delay is determined by the adjustment of the weights 165.

The teeth A, B and C are also arranged so as to permit the catch 137 to pass on after temporary engagement. This is because tooth A, B or C swings to the left, as the catch 137 passes upwardly. This permits ultimate complete ascent of a slider 35 after engaging, moving up,

and disengaging a tooth A, B or C, as the case may be.

The counterclockwise action brought about on the sector 131 by the rising catch 137 winds up the escapement spring 147, so that after the catch 137 disengages a tooth A, B or C, the escapement may run down in the reverse direction under action of said wound spring 147. This causes the sector 131 to return slowly toward its starting position (with delayed action) due to the escapement mechanism. It should be recalled in this respect that the escapement mechanism is of the reversing type, that is, it inserts inertia resistance to motion of the sector 131 in either direction of motion of the latter. The purpose of this will appear.

Operation of the mechanism so far described is as follows:

Assume that an overload currents occurs on the line 13, 15 and that the parts are in the closed-circuit condition shown in Figs. 1-5. The surge will instantaneously energize the solenoid 17, since the time lag of a solenoid is very small. This instantaneously rotates the lever 89 clockwise. Thus the extension 81 of lever 89 immediately withdraws the slide 81 from the catch 79. No matter how violent the action on the lever 89, this has substantially no deleterious force effects on the remainder of the operating linkage. Since the wound-up spring 121 is biasing the ratchet 109, by way of pawl 115, it then drives the crank 71 counterclockwise through the gear train 107, 105, 104 and shaft 73. The action proceeds only to the point shown in Fig. 8, because in tending to drive down the link 67 and the slide 35, resistance is encountered from the closed latch 57, 59.

The latch 57, 59 is in the closed position because it takes some time for the overload current through the bimetal thermostatic coil 21 to have its effect in generating heat and in causing shrinkage in the length of the coil. This provides the desirable inverse time-current characteristic above mentioned, that is, a heavy current for a short time will have an effect similar to a lighter current for a longer time, considering each on an overload basis. Current which is considered to be of the non-overload variety will not energize the solenoid armature 99, nor shorten the coil 21 sufficiently to open the latch 57, 59. Current of an overload amount flowing for an insufficient time, although it has operated the solenoid release, may not operate to release the latch 57, 59; in which event the circuit will not open.

Overload current flowing for a predetermined time will effect opening of the latch 57, 59, by shrinkage of coil 21 operating to move the arm 25 counterclockwise, thus lifting the link 63 and moving the bell-crank 55 counterclockwise. When this latch 57, 59 is released, biased crank 71 drives the linkage 67, 35, the slide 35 being driven down to open the circuit. Continued rotation of the crank 71 then promptly starts the slider up toward reclosing the circuit; but at this time the catch 137 engages under the tooth A of the sector ratchet 131 (see Fig. 9). Therefore, upon the upward movement of the slider 35, the escapement mechanism is temporarily engaged as indicated in Fig. 9, and the sector 131 is driven to the position shown in Fig. 10. This introduces the time-delay action during the reclosing action. As the tooth A moves to the left and disengages, catch 137 is released and the circuit recloses.

Assuming that upon the first reclosure of the

circuit, that which caused the overload current has not cleared the line, this means that the solenoid 17 has not yet been de-energized. Hence the slide 81 is not back in position to block the second cycle of movement of the catch 79. Nor is the latch 57, 59 reclosed. Therefore nothing is in the way of the spring 121 continuing to drive the mechanism 71, 67, 35 (through gear train 107, 105, 104 and shaft 73). The result is that the slide 35 is again driven through an opening cycle. However, in the meantime the sector 131 has not had time to run back very far from the position shown in Fig. 10, wherein the next tooth B is in position to be engaged by the catch 131, the next time the catch rises. Thus, upon the second cycle of action, the catch 131 slides down past the horizontally positioned tooth B, and upon rising catches that tooth further to drive the sector 131 counterclockwise with delayed action. Tooth B also finally moves to the left to release 131 for the second delayed circuit reclosure.

If upon the second delayed reclosure the line has not yet cleared, a third reopening of the circuit will occur in the manner above described for the first and second opening, but at this time the tooth C of the sector 131 is horizontal (its return also having been delayed) and it (tooth C) will be caught by the catch 131 moving up for the third time (Fig. 11). In this instance, however, the delay is indefinitely long, because by this time the tail piece 133 of sector 131 contacts the stop 135, thus permanently hanging the mechanism in circuit open position until some manual action is taken to reclose it. In other words, when a fault occurs, the apparatus will cause one opening and one delayed reclosure, then a second opening and a second delayed reclosure, and then a third opening, without a third reclosure until steps are taken manually to reclose, preferably after the line has been cleared.

If some transient phenomenon has caused the trouble and clears before the third opening of the circuit, the solenoid 17 will have been de-energized so that the solenoid spring 101 will have set the lever 89 to insert slide 81 under the catch 79. Thus the further driving action on the mechanism from the spring 121 is resisted. In the meantime, the thermostatic coil 27 will have cooled down to its state corresponding to normal current flow. Its consequent lengthening will have depressed the link 63 and will have placed the latch 57, 59 in position to close, so that subsequent circuit openings cannot occur.

Assuming next that the overload fault is of such duration that the device operates repeatedly as above described, finally to hang it in open-circuit position, this will require a means for manually reclosing the circuit by a lineman after repairs have been made. The linkage for this purpose comprises a bell-crank 169 pivoted at 171 to an extension from the frame 49. This carries a convex pad 173 which cooperates with a dog 175 attached to the lower end of the link 139. This dog is normally biased counterclockwise by a spring 171 to a downward position wherein a tail stop 179 rests against the left side of link 139. Therefore, if the bell-crank 169 is manually rotated counterclockwise, the pad 173 will push the dog 175 to the right, provided the dog 175 is down as is the case when the mechanism is in open-circuit position as shown in Fig. 12. This action results in counterclockwise motion of the link 139, which frees the catch 131 from behind tooth C. As soon as this release is made, the tension spring 45 contracts and drives up the 75

slider 35 to closed circuit position. In Fig. 12 the manual reclosing action is proceeding without having been completely consummated.

However, the device is trip free, since if the bell-crank 169 is moved or held counterclockwise, as just above described, before the fault has been cleared, on the next downward switch opening stroke of the slider 35, the dog 175 simply folds up in coming down upon the pad 173 (see Fig. 14). Thus the bell-crank 169 is prevented from pushing the lever of the link 139 to the right and the pick-up action of the catch 131 occurs on the tooth C, whereupon the permanent open condition is again reached. Tooth C is the one engaged at this time, because time-delay action has prevented it from returning to the Fig. 1 position. Under this set of conditions the latch 57, 59 of course remains open due to the shortened condition of the warm bimetal thermostat 27, and the slide 81 remains pulled out from the catch 79, because the solenoid remains energized.

In general, only one reclosure and reopening occurs under the trip-free action, because presumably when the closing operation is attempted the switch is open and the sector 131 is then in the Fig. 11 position. Therefore release of the catch 131 from behind the tooth C would simply result in one reclosure and a reopening with a recatching behind the tooth C which will not have had time to return in view of the delay caused by the escapement mechanism. However, the device is also trip free even if several operations are required for reopening, as when the reclosing operation starts with tooth A horizontal as in Figs. 1.

In order conveniently to operate the bell-crank 169, a depending link 181 is pivoted to it at 183, which may be operated from below. The link 181 also extends up and is biased upward by 40 means of a spring 185 carried on an extension 187 from the frame 49.

There is another operating characteristic desired, which is facility for manually permanently opening and reclosing the circuit, as desired, under conditions of no fault. This allows for control of the circuit for working on it.

The linkage for this purpose consists of a rocker 189 pivoted on the frame at 191 and having a lost-motion pin and slot connection 193 with the link 181. This rocker 189 is biased clockwise by a spring 195. At its right-hand end, a catch 197 is pivoted at 199. This catch 197 is pulled counterclockwise by means of the spring 201 reacting from the rocker 189 itself. At the left, the rocker 189 is provided with a depending operating link 203 which may be pulled down or pushed up.

The lost-motion connection 193 allows the recloser bell-crank 169 to be operated independently of complete operation of the hold-open rocker 189, but not vice-versa. Therefore, if under normal closed conditions of the circuit, the lever 203 is pulled down, the link 181 also will be operated while the rocker 189 is rotated counterclockwise. This will place the catch 197 up and to the left. Then when the link 67 is driven down, a platen 205 thereon will be caught by the catch 197 as indicated in Fig. 13.

For the link 67 to be driven down at this time, the slide 81 must be pulled to the left and the latch 57, 59 must be opened. It is for this purpose that the link 181 is extended upward for obtaining a pivot connection 207 with a double bell-crank 209.

Withdrawal of the plate 81 is effected by con-

necting to the upper leg of the double bell-crank 209 a link 213 which is curved in horizontal view as shown in Fig. 6. This link 213 has an extension 215 which rides through an opening 216 and is formed as a cam 217. It is normally biased upward by a spring 219. When the links 203, and consequently 181, are pulled down and the double bell-crank 209 is rotated counterclockwise, this drives the link 213 to the left. Its end 221 contacts a lug 223 on the plate 81, thus drawing the plate out from the catch 197 and permitting the circuit opening action from power spring 121.

Another leg of the bell-crank 209 (the lower leg) is connected to a push link 212 which has a lost motion connection at 214 with a pin 218 on the latch bell-crank 55. This effects release 15 of the latch 57, 59 at the time the links 203 and 181 have been pulled down toward their lower 20 and lower limits.

Opening is made permanent by the catching 25 action of the catch 197 on the platen 205 when the latter is at its lowest position. The parts are 30 then in the position shown in Fig. 13.

To reclose the circuit under no-fault conditions, the link 203 is pushed up. This releases 35 the catch 197 from the platen 205 and allows the slider 35 under action of springs 45 and 21 to rise with time delay due to tooth A, thus closing 40 the circuit with time delay. The plate 81 and latch 57, 59 return to holding positions through 45 action of spring 185. Therefore the circuit remains shut.

The purpose of the cam 217 (Figs. 1, 4 and 6) 50 is to depress the end 221 of the plate-operating link 213 during the terminal portions of its stroke. Thus the plate 81 may return to holding position.

It will be understood that the described escape- 55 ment time-delay mechanism is quite convenient for obtaining the time-delay action in both directions of movement thereof, but that other time-delay mechanisms may be adapted to the purpose.

The link 181 may be referred to as a recloser 60 handle. The depending link 203 may be referred to as a hold-open and recloser handle.

The power spring 121 has enough energy to 65 operate the device for many reclosing strokes, for example, fifty, before rewinding is necessary.

The advantage of having the solenoid control 70 for releasing the reclosing linkage for operation, in addition to the thermostatic control, is that it instantaneously stops cycling movement of the reclosing mechanism when a fault clears, whereas it would take some time for the thermostatic control alone to have its effect on stopping the operation of the cycling reclosing mechanism. Thus such a quick-operating device as the solenoid or its equivalent is the only type that can be depended upon to stop the cycling action short of continuing the operation until the switch remains open. Since the latter condition is only desired when the fault does not clear quickly, it will be seen that the quick-acting solenoid control serves the function of conserving, to a minimum, switch opening and closing operations when the overload promptly clears.

It will be seen that an advantage of the invention is that operation is not driven to its limit by two reclosures and three circuit-opening operations unless these occur in direct and continuous succession. If successive individual operations (circuit opening and reclosing) occur discontinuously, as many may happen, the main spring is capable of effecting, for example, fifty

operations on fifty successive days. This is because after a single operation (opening and reclosing) the escapement mechanism always returns to its initial position ready for another operation. It is only three openings in succession that brings about permanent opening.

Another advantage of the device is that its inverse time-current characteristics are similar to the time-current overload characteristics of 10 transformers, and it can therefore be readily designed to be organized with them.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted 20 as illustrative and not in a limiting sense.

We claim:

1. A reclosing repeater switch comprising a mechanism movable through repeating cycles to open and close the switch during each cycle, means biasing the mechanism to cycle, a catch normally biased to prevent cycling, a solenoid responsive to overload current adapted to withdraw the catch, a latch preventing development of cycling despite removal of said catch, and 25 means responsive to overload current but having a time lag with respect to the solenoid for releasing said latch to effect cycling of the mechanism under its bias.

2. A reclosing repeater switch comprising a mechanism movable through repeating cycles to open and close the switch during each cycle, means biasing the mechanism to cycle, a catch normally biased to prevent cycling, a solenoid responsive to overload current adapted to withdraw the catch, a latch preventing development of cycling despite removal of said catch, thermostatic means responsive to overload current but having a time lag with respect to the solenoid for releasing said latch, and time-delay means 40 adapted automatically to couple with the cycling mechanism when the latter operates toward switch closing position.

3. A reclosing repeater switch comprising a mechanism movable through repeating cycles to open and close the switch during each cycle, means biasing the mechanism to cycle, catch means biased to prevent cycling, a solenoid responsive to overload adapted to withdraw the catch, a latch preventing development of cycling 50 despite removal of said catch, means responsive to overload but having a time lag with respect to the solenoid for releasing said latch, time-delay means adapted automatically to couple with the cycling mechanism when the latter operates toward switch closing position, said time-delay means being biased toward an initial position and operating with time delay in returning to said initial position, the time-delay means having means whereby it may be coupled to and 55 released from said cycling means at any of various positions of the time-delay means.

4. A reclosing repeater switch comprising a mechanism movable through repeating cycles to open and close the switch during each cycle, means biasing the mechanism to cycle, catch 60 means biased to prevent cycling, a solenoid responsive to overload adapted to withdraw the catch to permit cycling, a latch preventing development of cycling despite removal of said catch, means responsive to overload but having 65

a time lag with respect to the solenoid for releasing said latch, time-delay means adapted automatically to couple with the cycling mechanism when the latter operates toward switch closing position, said time-delay means being biased toward an initial position and operating with time delay in returning to said initial position, the time-delay means having means whereby it may be coupled to and released from said cycling means at any of various positions of the time-delay means until a final position is reached in which coupling is effected but uncoupling between the time-delay means and the cycling means cannot occur, whereby the switch is maintained open, and manual means for uncoupling the time-delay means and the cycling means for manual switch reclosure.

5. A reclosing repeater switch comprising a mechanism movable through repeating cycles to open and close the switch during each cycle, means biasing the mechanism to cycle, catch means biased to prevent cycling, a solenoid responsive to overload adapted to withdraw the catch to permit cycling, a latch preventing development of cycling despite removal of said catch, means responsive to overload but having a time lag with respect to the solenoid for releasing said latch, time-delay means adapted automatically to couple with the cycling means when the latter operates toward switch closing position, said time-delay means being biased toward an initial position and operating with time delay in returning to said initial position, the time-delay means having means whereby it may be coupled to and released from said cycling means at any of various positions of the time-delay means until a final position is reached in which coupling is effected but uncoupling between the time-delay means and the cycling means cannot occur, whereby the switch is maintained open, manual means for uncoupling the time-delay means and the cycling means, whereby the switch may be reclosed, under normal load conditions, and means for cyclically operating the switch to permanent open position under conditions of overload despite manual operation toward closed circuit position of the switch.

6. A reclosing repeater switch comprising a mechanism movable through repeating cycles to open and close the switch during each cycle, means biasing the mechanism to cycle, catch means biased to prevent cycling, a solenoid responsive to overload adapted to withdraw the catch, a latch preventing development of cycling despite removal of said catch, means responsive to overload but having a time lag with respect to the solenoid for releasing said latch, time-delay means adapted automatically to couple with the cycling means when the latter operates toward switch closing position, said time-delay means being biased toward an initial position and operating with time delay in returning to said initial position, the time-delay means having means whereby it may be coupled to and released from said cycling means at any of various positions of the time-delay means until a final position is reached in which coupling is effected but uncoupling between the time-delay means and the cycling means cannot occur, whereby the switch is maintained open, manual means for uncoupling the time-delay means and the cycling means, whereby the switch may be reclosed, means for cyclically operating the switch to permanent open position under conditions of overload despite

7. A reclosing repeater switch comprising a mechanism movable through repeating cycles to open and close the switch during each cycle, means biasing the mechanism to cycle, catch means biased to prevent cycling, a solenoid responsive to overload adapted to withdraw the catch, a latch preventing development of cycling despite removal of said catch, means responsive to overload but having a time lag with respect to the solenoid for releasing said latch, time-delay means adapted automatically to couple with the cycling means when the latter operates toward switch closing position, said time-delay means being biased toward an initial position and operating with time delay in returning to said initial position, the time-delay means having means whereby it may be coupled to and released from said cycling means at any of various positions of the time-delay means until a final position is reached in which coupling is effected but uncoupling between the time-delay means and the cycling means cannot occur, whereby the switch is maintained open, manual means for uncoupling the time-delay means and the cycling means, whereby the switch may be reclosed, means for cyclically operating the switch to permanent open position under conditions of overload despite manual operation toward closed circuit position of the switch, manually operable means for releasing both the catch and the latch, whereby under normal conditions the cycling means drives the switch shut, and manually operable means cooperating with said last-named means for latching the cyclically operating means in mid-cycle to prevent switch closing under normal current conditions.

8. Electrical reclosing apparatus comprising circuit contacts, a switch movable to open and close a circuit through the contacts, a solenoid having a winding and an armature and a thermostatic element electrically connected in series with said winding and with said switch when the latter is closed, said thermostatic element being adapted to heat and move in response to overload current, a movable linkage connected to the switch for driving it open and shut, and mechanical control connections from the solenoid armature and the thermostatic element to the linkage for cooperatively releasing it for motion, whereby the switch is opened and closed in response to overload current.

9. Electrical reclosing apparatus comprising circuit contacts, a switch movable to open and close a circuit through the contacts, a solenoid and a thermostatic element in series with one another and said switch when the latter is closed, said thermostatic element being adapted to heat and move in response to overload current, a movable linkage connected to the switch for driving the latter open and shut, and control connections from the solenoid and the thermostatic element to the linkage for releasing the linkage for motion in response to overload current.

10. Electrical reclosing apparatus comprising circuit contacts, switch means movable to open and close a circuit through the contacts, a mechanism connected to the switch and adapted to operate through a cycle to open the switch and subsequently to close it, a first and a second operating release for the mechanism holding it

against its bias, electrical means operative instantaneously in response to overload current substantially regardless of the value of said overload current to energize the first release, and electrical means also responsive to overload current but having substantially inverse time-current characteristics for operating the second release.

11. Electrical reclosing apparatus comprising circuit contacts, a switch movable to open and close a circuit through the contacts, a mechanism connected to the switch and biased to operate through a cycle to open the switch and subsequently to close it, a first and a second control for the mechanism normally blocking its motion against its bias, solenoid means operative instantaneously in response to overload current substantially regardless of the value of said overload current to release the first control, and thermostatic electrical means responsive to overload current with substantially inverse time-current characteristics for releasing the second control, whereby the mechanism may move to open and close the switch.

12. Electrical reclosing apparatus comprising circuit contacts, a switch movable to open and close a circuit through the contacts, a mechanism connected to the switch and biased to operate through a cycle to open the switch and subsequently to close it, a first and a second control for the mechanism normally blocking its motion against its bias, solenoid means operative instantaneously in response to overload current substantially regardless of the value of said overload current to release the first control, thermostatic electrical means responsive to overload current with substantially inverse time-current characteristics for releasing the second control, whereby the mechanism may move to open and close the switch, and time-delay means connected with said mechanism to delay reclosing movement.

13. Electrical reclosing apparatus comprising circuit contacts, a switch movable to open and close a circuit through the contacts, a mechanism connected to the switch and biased to operate through a cycle to open the switch and subsequently to close it, a first and a second control for the mechanism holding it against its bias, electrical means operative instantaneously in response to overload current substantially regardless of the value of said overload current to release the first control, and electrical means having substantially inverse time-current characteristics for releasing the second control, said instantaneously operable means comprising a solenoid and said inverse time-current means comprising a composite metallic thermostat.

14. Electrical reclosing apparatus comprising circuit contacts, a switch movable to open and close a circuit through the contacts, a mechanism connected to the switch and biased to operate repeatedly through cycles and opening and closing the switch, a first control means and a second control means each adapted to block and release the mechanism for cycling movement, a solenoid responsive to overload current instantaneously to operate the first control to release the mechanism and responsive to normal current to operate the first control instantaneously to block cycling movement, and a thermostatic means responsive to overload current to operate the second control to release the mechanism for cycling and responsive to normal current to operate the second control to block the mechanism

against cycling, said thermostatic means operating with inverse time-current characteristics.

15. Electrical reclosing apparatus comprising circuit contacts, a switch movable to open and close a circuit through the contacts, a mechanism connected to the switch and biased to operate repeatedly through cycles to open and close the switch, time-delay means delaying each reclosure but after a predetermined number of continuously successive cycles indefinitely blocking reclosure, a first control means and a second control means each adapted to block and release the mechanism for cycling movement, a solenoid responsive to overload current instantaneously to operate the first control to release the mechanism and responsive to normal current to operate the first control instantaneously to block cycling movement, a thermostatic means responsive to overload current to heat to operate the second control to release the mechanism for cycling and responsive to normal current to operate the second control to block the mechanism against cycling, said thermostatic means operating with inverse time-current characteristics.

16. Electrical reclosing apparatus comprising circuit contacts, a switch movable to open and close a circuit through the contacts, a mechanism connected to the switch means and biased to operate repeatedly through cycles opening and closing the switch, time-delay means delaying each reclosure but after a predetermined number of continuously successive cycles indefinitely blocking reclosure, manual means for releasing the blocking to effect reclosure, a first control means and a second control means each adapted to block and release the mechanism for cycling movement, a solenoid responsive to overload current instantaneously to operate the first control to release the mechanism and responsive to normal current to operate the first control instantaneously to block cycling movement, a thermostatic means responsive to overload current to heat to operate the second control to release the mechanism for cycling and responsive to normal current to operate the second control to block the mechanism against cycling, said thermostatic means operating with inverse time-current characteristics.

17. Electrical reclosing apparatus comprising circuit contacts, a switch movable to open and close a circuit through the contacts, a mechanism connected to the switch means and biased to operate repeatedly through cycles opening and closing the switch, time-delay means delaying each reclosure but after a predetermined number of continuously successive cycles indefinitely blocking reclosure, manual means for releasing the blocking to effect reclosure, a first control means and a second control means each adapted to block and release the mechanism for cycling movement, a solenoid responsive to overload current instantaneously to operate the first control to release the mechanism and responsive to normal current to operate the first control instantaneously to block cycling movement, a thermostatic means responsive to overload current to heat to operate the second control to release the mechanism for cycling and responsive to normal current to operate the second control to block the mechanism against cycling, said thermostatic means operating with inverse time-current characteristics and means for making said manual reclosure means trip free.

18. Electrical reclosing apparatus comprising circuit contacts, a switch movable to open and

close a circuit through the contacts, a mechanism connected to the switch and biased to operate repeatedly through cycles to open and close the switch, a first control means and a second control means each adapted to block and release the mechanism for cycling movement, a solenoid responsive to overload current instantaneously to operate the first control to release the mechanism and responsive to normal current to operate the first control instantaneously to block cycling movement, a thermostatic means responsive to overload current to heat to operate the second control to release the mechanism for cycling and responsive to normal current to operate the second control to block the mechanism against cycling, said thermostatic means operating with inverse time-current characteristics, time-delay means associated with said mechanism for delaying each reclosure until a predetermined number of continuously successive reclosures has occurred, after which it indefinitely delays reclosure, manual means for reclosing the time-delay means, means for making said manual releasing means trip free, and manual means for releasing the time-delay means and blocking the mechanism against reclosure operation, whereby the switch under normal load conditions may be held open.

19. A switch recloser comprising a switch opening and reclosing linkage, means biasing the linkage to pass through a cycle of operation to open and reclose the switch, catch means cooperating with the linkage and normally positioned to resist the bias, a solenoid adapted to set said catch means to release the linkage for initial biased movement, a latch associated with the linkage adapted when closed to prevent development of said initial movement, and a thermostatic element adapted in response to heating caused by excess current therethrough to open said latch to permit complete cyclic movement of the switch through an open to a reclosed condition.

20. A switch recloser comprising a switch opening and reclosing linkage, means biasing the linkage to pass through a cycle of operation to open and reclose the switch, catch means cooperating with the linkage and normally positioned to resist the bias, a solenoid in said circuit adapted to set said catch means to release the linkage for initial biased movement, a latch associated with the linkage adapted when closed to prevent development of said initial movement, and a current-heated thermostatic element in series with said solenoid and adapted in response to heating caused by excess current therethrough to open said latch to permit complete cyclic movement of the switch through an open to a reclosed condition, said solenoid and thermostat being also connected in series with the switch.

21. A switch recloser comprising a switch opening and reclosing linkage, means biasing the linkage to pass through a cycle of operation to open and reclose the switch, catch means cooperating with the linkage and normally positioned to resist the bias, a solenoid in series in the circuit served by the switch, the solenoid being adapted when energized to set said catch means to release the linkage for initial biased movement, a latch associated with the linkage adapted when closed to prevent development of said initial movement but at any time permitting the final closing movement, and a thermostatic element in series with said solenoid in said circuit and adapted in response to heating caused by excess current therethrough to open the latch, said catch means being

adapted automatically to prevent a continued biased operation of the linkage provided said solenoid is deenergized.

22. A switch recloser comprising a linkage biased to pass through a cycle of operation to open and reclose the switch, catch means cooperating with the linkage and normally positioned to resist such bias, a solenoid adapted to set said catch means to release the linkage for initial biased switch opening movement, a latch associated with the linkage adapted when closed to prevent development of said initial switch opening movement but at any time permitting the final switch closing movement, a thermostatic element in series with said solenoid and adapted in response to heating caused by excess current therethrough to open the latch, to permit complete opening and reclosing movement, and time-delay means adapted automatically to be coupled to said linkage when the latter moves toward switch closing position.

23. A reclosing repeater switch comprising a linkage biased to pass through a cycle of operation, catch means cooperating with the linkage and normally positioned to resist such bias, a solenoid in the circuit served by the switch to set said catch means to release the linkage for bias movement, switch contacts in said circuit, a member movable back and forth to open and close the contacts respectively and coupled to said linkage for contact opening movement during initial linkage movement and for contact closing movement during final linkage movement, a latch when closed preventing said initial opening movement but at any time permitting the final closing movement, a thermostatic element in series with said solenoid and adapted in response to heating caused by excess current therethrough to open the latch, time-delay means adapted automatically to couple to said movable member when the latter moves toward switch closing position, said time-delay means being biased toward an initial position and operated against bias during said switch closing action of the movable member and being adapted to return with time delay toward its initial position, and means associated with said time-delay means for making connection therewith at any of the positions which it may assume in its time-delay return action during switch open periods.

24. A reclosing repeater switch comprising a linkage biased to pass through a cycle of operation, catch means cooperating with the linkage and normally positioned to resist such bias, a solenoid in the circuit served by the switch and responsive to overload to set said catch means to release the linkage for bias movement, the catch means being adapted automatically to return to blocking position upon cessation of the overload, switch contacts in said circuit, a member movable back and forth to open and close the contacts respectively and coupled to said linkage for contact opening movement during initial linkage movement and for contact closing movement during final linkage movement, a latch which when closed prevents said initial opening movement but at any time permits the final closing movement, a thermostatic element in series with said solenoid and adapted in response to heating caused by excess current therethrough to open the latch, time-delay means adapted automatically to couple to said movable member when the latter moves toward switch closing position, said time-delay means being biased toward an initial position and op-

erated against bias during said switch closing action of the movable member and being adapted to return with time delay toward its initial position, and means associated with said time-delay means for making connection therewith at any of the positions which it may assume in its time-delay return action during switch open periods.

25. A reclosing repeater switch comprising cycling means for successively opening and closing the switch, a solenoid in series with the switch, a thermostat responsive to heating caused by excessive current in series with said solenoid and switch, means responsive to energization of the solenoid by excess current adapted merely to initiate movement of the cycling means, and means responsive to normal current and heating of the thermostat adapted to prevent further movement of the cycling means but in response to excess current and heating of the thermostat adapted to permit said movement through a switch opening and to a switch closing condition.

26. A reclosing repeater switch comprising cycling means for successively opening and closing the switch, a solenoid in series with the switch, a thermostat responsive to heating caused by excess current also in series with said solenoid and switch, means responsive to energization of the solenoid by excess current adapted merely to initiate movement of the cycling means, means responsive to normal current and heating of the thermostat adapted to prevent further movement of the cycling means but in response to excess current and heating of the thermostat adapted to permit said movement through a switch opening and to a switch closing condition, and means biasing the solenoid-operated means toward its initial position to prevent actuation of the cycling means.

27. A reclosing repeater switch comprising 40 cycling means for successively opening and clos-

ing the switch, a solenoid in series with the switch, a thermostat responsive to heating caused by excess current in series with said solenoid and switch, means responsive to energization of the solenoid by excess current adapted merely to initiate movement of the cycling means, means responsive to normal current and heating of the thermostat adapted to prevent further movement of the cycling means but in response to excess current and heating of the thermostat adapted to permit said movement through a switch opening and to a switch closing condition, means biasing the solenoid-operated means toward its initial position, and time-delay means adapted initially to delay reclosure operation and finally to prevent it altogether.

28. A reclosing repeater switch comprising cycling means for successively opening and closing the switch, a solenoid in series with the switch, a thermostat responsive to heating caused by excess current in series with said solenoid and switch, means responsive to energization of the solenoid by excess current adapted merely to initiate movement of the cycling means, means responsive to normal current and heating of the thermostat adapted to prevent further movement of the cycling means but in response to excess current and heating of the thermostat adapted to permit said movement through a switch opening and to a switch closing condition, means biasing the solenoid-operated means toward its initial position, time-delay means adapted initially to delay reclosure operation and finally to prevent it altogether, and manual means for releasing the connection between the switch operating means and said time-delay means.

THEODORE BIRKENMAIER.
CARL E. MOSLEY.

DISCLAIMER

2,321,122.—*Theodore Birkenmaier, St. Louis, and Carl E. Mosley, Overland, Mo.*
RECLOSING CIRCUIT BREAKER. Patent dated June 8, 1943. Disclaimer
filed August 14, 1944, by the assignee, W. N. Matthews Corporation, the
inventors, assenting and concurring.

Hereby disclaims claims 1 to 4 inclusive, 10 to 16, inclusive, and 25, 26, 27, and
28 of said patent.
